UNITED STATES PATENT OFFICE.

HARRY BRIDGMAN SMITH, OF BROOKLYN, NEW YORK.

PAPER-BOX SHELL.

1,365,351.

Specification of Letters Patent. Patented Jan. 11, 1921.

Application filed January 24, 1919, Serial No. 272,907. Renewed December 1, 1920. Serial No. 427,655.

To all whom it may concern:

Be it known that I, HARRY BRIDGMAN SMITH, a citizen of the United States, residing at Brooklyn, in the county of Kings and 5 State of New York, have invented new and useful Improvements in Paper-Box Shells, of which the following is a specification.

This invention relates to improvements in paper box construction, pertaining more particularly to structures in which the cover blank is applied in what is generally known in the trade as a "loose wrap" formation.

Box construction of this type, as generally produced, has been along the lines disclosed 10 in the patent to P. S. Smith, No. 912,746, February 16, 1909, wherein the cover blank is applied to a "set-up" shell, the blank being applied in such manner as to produce this loose wrap effect, viz.: a non-adhesive connection of the blank to the outer faces of the shell, the adhesive connection being applied along the marginal edges of the covering blank which, in the finished product, are infolded on to the interior faces of the 20 standing walls of the shell.

Certain difficulties are present in such construction, among which are those produced by the bunching of marginal edge portions at the corners during the inturning of the 25 edges, difficulties which have been overcome to a certain extent by the use of certain mechanisms.

I have found, however, that these and other difficulties can be avoided to a considerable extent by assembling the shell and cover blanks "in the flat"—in advance of any setting-up of the shell blank, this possibility being presented in companion applications. Where, however, the assembly is in the flat, 35 and especially where the shell blank is of a type to provide multi-ply end wall configurations in the set-up shell, the manner in which the side and end wings and laps of the shell blank are required to be folded present 40 other problems where the construction is being utilized under quantity production conditions. One of these problems is provided by the fact that the end wall configuration is of more than one ply while the assembly in 45 the flat—provided by inturning the marginal edges of the side wings of the cover blank and adhesively connecting them to the opposite face of the shell blank—would include but a single ply within the marginal 50 edge overlying the side wing laps, the result

being that in the set up condition the marginal edge of the upstanding end wings—the inner 60 ply of the end wall of the shell—would be exposed excepting at such portion as would be covered by the end wing of the cover blank which is applied after the shell has been set up; as the applied end wing of the cover blank does not extend the full width 65 of the shell—the length of the end walls—an exposed or "raw" edge would be presented on opposite sides of the applied end wing, materially affecting the general appearance of the finished box shell.

This particular problem is met in a companion application by retaining a portion 70 of the side wing marginal edges of the cover blank unapplied until after the shell blank end configuration is in set up formation, permitting the application to be made to the double ply thickness. This, however, practically requires slitting of the cover blank at proper points to enable a portion of the 75 marginal edge to be applied in the flat while these portions remain unapplied, thus tending to add to the cost of manufacture in this respect.

The present invention is designed to meet this general problem in a different manner, retaining the advantages of an assembly "in the flat" and at the same time eliminating 80 the necessity of slitting the cover blank. This result is obtained by changing the form of the shell blank in certain respects—a change which does not affect the ability to produce it in the usual manner—and applying 85 the marginal edges of the cover blank side wings throughout the length of the marginal edges and while both blanks are in the flat. The particular change in shell blank is the cutting away of a small section at the 90 outer corners of the end wings of the shell blank—the portion of the wings which would normally fall beneath the slitted portions of the companion application. The vertical length of the cut-away portion may 95 vary, but should not extend the entire depth of the box shell; and the horizontal length is preferably, although not essentially, sufficient to carry the vertical wall of the recess into underlying relation to the applied end 100 wing of the cover blank. The omission of the sections obviously carry the margin of the shell end wings on practically two planes, the portion covered by the cover blank end wing extending to the top-plane 105 110

of the shell, while those portions not covered extend to a plane below and spaced from such top plane.

As a result, the upper margin of the shell 5 end wings in the plane of the top of the shell presents the finished edge-covered appearance, since the shell side wing laps—which extend to such plane and form the outer ply of the end configuration—receive their covering while the blanks are in the flat. When 10 the shell is filled, the raw edge produced by the horizontal wall of the cutaway portion is below the level of the contents and therefore unnoticed; when the contents are removed, 15 the appearance is not materially affected, since the raw edge tends to give the appearance of an inserted member at the ends of the shell.

To these and other ends, therefore, said 20 invention consists in the improved construction and combination of parts hereinafter fully described, illustrated in the accompanying drawings and more particularly pointed out in the appended claims.

25 In the accompanying drawings, in which similar reference characters indicate similar parts in each of the views,

Figure 1 is a perspective view showing an assembly of the cover and shell blanks in the 30 flat, the view also showing, in dotted line outline, the particular shape of the shell blank employed in the assembly.

35 Figs. 2, 3 and 4 are perspective detail views showing progressive stages in the folding of the assembly of Fig. 1.

Fig. 5 is a detail sectional view of the folded assembly, the section being taken through the end wall formation.

40 Fig. 6 is a perspective view of a completed shell.

For the purpose of illustrating the invention, simple forms of blanks are shown, these being illustrative of a general type which may be varied to meet individual 45 needs or service conditions. The illustration is of blanks adapted to produce a shell in which the end-walls are of the multi-ply formation with the end wing of the shell blank forming the inner ply.

50 The shell blank, indicated generally at A, is of the usual general form, modified in certain respects, the blank having the body portion a, side wings a', end wings a² and laps a³ at the ends of the side wings. The blank 55 may be scored, if desired, the scoring being indicated by the dot and dash lines. The modification of the general form of the blank consists in changing the outer edge configuration of the end walls by cutting away or omitting sections at the opposite 60 ends of these wings, this omission being indicated at a⁴, and shown as of rectangular contour, with the dimensions such as to locate the horizontal wall or edge on a different or lower plane than the normal edge

when the wing is in its upstanding position, and the vertical wall located at a point where it may underlie the infolded end wing of the cover blank.

The cover blank, indicated at B, is also 70 of a general formation, carrying a body portion b, end wings b', side wings b², and what may be considered as wing laps b³, these latter being the extended portions of the side wings. The wings and laps of the cover 75 blank are of greater width than the width of the similar parts of the shell blank to provide margins, these margins preferably carrying adhesive zones. The parts of the cover blank do not conform in dimensions 80 with the similar parts of the shell blank, this being one of the general characteristics of structures formed under "loose-wrap" conditions.

As heretofore pointed out, one general 85 difference over the prior practice of applying the cover blank, is that I assemble the two blanks while "in the flat," the shell blank being placed in proper position on the cover blank, after which the margins of 90 the side wings b² and their laps are turned over the marginal edges of and adhesively secured to the upper faces of side wings a' and their laps a³ as shown in Fig. 1.

This provides the embryo assembly, in 95 which the application of the cover blank is completed so far as the side of the shell blank is concerned, this inturning of margins also applying the major cover to the upper edge of the laps a³.

100 End wings a² of the shell blank are then raised to upstanding position, as in Fig. 2, followed by raising of side wings a', this latter raising placing laps a³ in position where they can be folded inward upon the 105 upstanding end wings, as in Fig. 3, so that the inturned marginal portions b³ of the cover will lie between adjacent faces of laps a³ and end wings a². Since the margins of the laps a³ are covered, this folding brings 110 the cover blank into position where the end wings b' can be given the usual doubled or gusset fold formation, as shown in this figure, this formation then being raised as in Fig. 4, and the margin b¹ inturned over 115 the end wall edges and infolded into securing relation on to the inner face of wings a², as in Fig. 6; this inturning placing a portion of the wing margins in overlying relation to the previously covered edges of 120 laps a³ and, with a blank having the cut-away dimensions indicated, concealing the vertical edges of the cut-away portions, producing the general appearance indicated in Fig. 6.

125 As will be understood, the horizontal edges of the cut-away section remain uncovered, but being on a lower plane than the top of the shell, the "raw edge" does not detract from the general appearance of the 130

finished shell since it is not brought into direct comparison with the covered edge of laps a^3 —as would be the case if the sections a^4 were retained; and when the shell is filled, 5 this exposed raw edge is generally located below the filling level and therefore concealed, so that the finished appearance of the shell is maintained. And where the blanks are properly proportioned, this general formation may add to the attractiveness of the 10 empty shell, in that it gives the appearance of the presence of an inserted member within the shell, seemingly strengthening the latter.

15 As will be understood, this change from prior practice is of exceeding importance from a manufacturing standpoint. It permits of assembly of the blanks in the flat, thus eliminating the difficulties relative to 20 bunching at the corners where infolding is attempted with the cover blank application to a set-up shell. It permits of the application of the margin to the shell laps as a part of the assembly—incidentally eliminating the 25 necessity of slitting the cover blank and the difficulties incident thereto—without bringing about a set-up condition which would detract from the finished appearance—such as would be provided by leaving a raw edge exposed 30 side by side and in the same plane with a covered edge of the end wall formation. It requires only the manipulation of the end-wing margins of the cover blank when dealing with the set up shell, a simple 35 operation in connection with standard machines.

As a result, the completed shell is produced in a materially simpler manner without detracting from the appearance of the 40 product, thereby materially reducing the general cost of manufacture, a matter of vital importance in production and commercial conditions.

While I have herein disclosed one way in 45 which the invention may be embodied, it will be readily understood that changes or modifications therein may be found essential or desirable in meeting the exigencies of use, and I desire to be understood as reserving 50 the right to make any and all such changes as may be found desirable or necessary, in so far as the same may fall within the spirit and scope of the invention as expressed in the accompanying claims, when broadly construed.

55 As will be readily seen, practice of the invention greatly decreases the cost of manufacture through simplifying the methods employed in assembling the blanks and setting up the assembly into the completed product, this result being obtained by so assembling the blanks that portions of the side wing marginal edges will be located between the planes of adjacent plies of the 60 multi-ply end wall formations of the set-up

shell. It is to be understood therefore, that the invention is not limited to the particular shape of blanks or the product resulting, but includes the method of producing the product.

Having thus described my invention, what I claim as new is:—

1. A covered paper box shell of the loose-wrap type, comprising a shell blank foldable to produce a multi-ply end wall formation, and a covering blank applied thereto, 70 said blanks being assembled to provide a shell structure having those edges of its upstanding walls located in the plane of the open top of the shell covered, and having additional edges of such walls located intermediate said plane and the bottom plane of the shell.

2. A covered paper box shell of the loose-wrap type, comprising a shell blank foldable 80 to produce a multi-ply end wall formation, and a cover blank applied thereto, said blanks being assembled to provide a shell structure having those edges of its upstanding walls located in the plane of the open top of the shell covered, and having additional edges of such walls located intermediate said plane and the bottom plane of the shell and exposed on the interior of the shell.

3. A covered paper box shell of the "loose wrap" type, comprising a shell blank having wings and end laps foldable to produce a multi-ply end wall formation, and a cover blank applied thereto with marginal portions overlying and adhesively affixed to marginal edges of the wings and laps, 90 said blanks being folded to provide a shell structure having covered portions of the laps lying between adjacent plies.

4. A covered paper box shell comprising a shell blank having end wings and side wings with end laps foldable to produce a multi-ply end wall formation, and a cover blank applied exteriorly of the shell blank 100 with marginal portions overlying and adhesively affixed to marginal edges of said side wings and end laps, said blanks being assembled in the flat and folded to provide a shell structure, having covered portions of the laps lying between adjacent faces of the 110 wall plies, and said cover blank having gusset folds at the ends of the shell with marginal portions turned over the edges of the multi-ply walls and adhesively affixed to the 115 interior of the shell.

5. A covered box shell comprising a shell blank foldable to produce a multi-ply end wall formation and having its end wings recessed at opposite ends with the recesses extending inward from the plane of the marginal edge of the wings, and a cover blank applied to overlie the marginal edges of the upstanding walls of the shell blank 125 in the plane of the open top of the shell.

6. A covered box shell comprising a shell blank having side and end wings and laps foldable into upstanding positions to produce a multi-ply end-wall formation embodying the laps and end wings, and a cover blank applied thereto with marginal edges overlying marginal edges of the shell blank side wings and laps and with end wings overlying marginal edges of the upstanding 10 end-wall formation, the shell blank end wings being recessed inwardly in advance of the edge-covered portions of the shell blank laps.

7. A shell blank adapted for use in the formation of covered paper box shells of the 15 multi-ply end wall type, said blank comprising a body portion, side and end wings, and laps at opposite ends of and integral with the side wings, said end wings being recessed inwardly at opposite ends of the wing 20 outer edge to provide an edge contour extending in a plurality of planes.

In testimony whereof I have hereunto set my hand.

HARRY BRIDGMAN SMITH.
